UNITED STATES PATENT OFFICE.

CHARLES F. MOWLL, OF ARLINGTON, MASSACHUSETTS.

VENDING-BOX.

1,120,218.

Specification of Letters Patent.

Patented Dec. 8, 1914.

Application filed April 27, 1914. Serial No. 834,700.

To all whom it may concern:

Be it known that I, CHARLES F. MOWLL, citizen of the United States, residing at Arlington, in the county of Middlesex and 5 State of Massachusetts, have invented certain new and useful Improvements in Vending-Boxes, of which the following is a specification.

This invention relates to improvements in 10 vending boxes, more particularly to that class in which the lid is so attached to the box that it may be turned beneath the box to expose the contents of the box without detaching the top therefrom.

15 The principal object of the present invention is to simplify the construction and increase the efficiency and utility of devices of this character.

Another object of the invention is to provide 20 a simply constructed device of this character which may be inexpensively manufactured and adapted without material structural change to receptacles of various sizes and forms.

25 Another object of the invention is to provide a device of this character in which the lid or cover is so attached that it may be folded underneath the box without being disconnected therefrom and also so attached 30 that a sealing band or revenue stamp when attached need not be broken at more than one place when the lid is raised and folded beneath the box.

Another object of the invention is to provide 35 a device of this character which presents the same appearance as an ordinary box when closed, and in which the goods are as fully protected as in an ordinary box.

With these and other objects in view the 40 invention consists in certain novel features of construction as hereinafter shown and described and then specifically pointed out in the claim; and in the drawings illustrative of the preferred embodiment of the invention. 45 Figure 1 is a perspective view of an approved form of the device in closed position. Fig. 2 is a similar view with the lid or cover folded beneath the box. Fig. 3 is a transverse section with the parts arranged 50 as in Fig. 1. Fig. 4 is a transverse section with the parts arranged as in Fig. 2.

Corresponding and like parts are referred to in the following description and indicated in all the views of the drawings by the same 55 reference characters.

When cigar boxes as generally construct-

ed with the cover or lid hingedly united at one side are employed in show cases, show windows and similar localities, much room is lost and the neat and attractive arrangement of the goods rendered difficult by the presence of the raised cover, and to dispose the cover or lid out of sight without detaching it from the box the improvement herein shown and described has been devised.

The body of the box comprises the bottom 10, ends 11-12, front 13 and cover or lid 14. The ends 11-12 extend above the front and back a distance equal to the thickness of the cover or lid and the ends of the 70 latter bear against these elevated portions of the ends, as shown in Fig. 1.

The back 15 is formed with a recess indicated at 16 and which extends between the ends 11-12 which thus form the ends of the 75 recess. The recess 16 opens upwardly and outwardly and extends only part way down the rear side of the box, and hingedly united at 17 to the upper edge of the lower portion of the back is a supplemental back member 80 18, which fills the recess when in upper position as shown in Figs. 1 and 3, and folds against the lower portion of the back when in lower position as shown in Figs. 2 and 4. At its outer edge the supplemental back 85 member 18 is hingedly united as shown at 19 to the rear edge of the top or lid 14.

The hinges may be of any desired form, but are shown composed of strips of fabric as in ordinary cigar boxes, but it will be 90 understood that it is not desired to limit the invention to any specific form of hinge.

By this arrangement the box presents the same appearance when closed as an ordinary cigar box, and is in condition to receive the 95 revenue stamp in the usual manner, and then when the box is open, the lid or top may be readily disposed beneath the bottom of the box and is out of the way and enables a plurality of the boxes to be arranged in 100 close relation and without obscuring the contents. The lid or top will thus be preserved and retained in connected relation to the body of the box, and the well known and desirable trade shape and appearance of 105 cigar and similar boxes likewise retained.

Obviously any other commodity than cigars may be vended from a box embodying this invention, and the box may be of any suitable or desired dimension and configuration, according to the kind and quantity 110 of the commodity to be vended from each

box. A vending-box embodying this invention is practically as cheap to manufacture as the ordinary cigar-box, as the fancy label usually applied to the inside of the lid, carrying the brand and any other information, may be dispensed with and a card, or other similar device substituted therefor.

Having thus described the invention, what is claimed as new is:

10. A receptacle including a top and vertical members with a recess in one of the vertical

members, and a supplemental member hingedly united respectively to the top and to said recessed member and foldable within the recess in one position and against the 15 recessed member when in another position.

In testimony whereof I affix my signature in presence of two witnesses.

CHARLES F. MOWLL.
